UNITED STATES PATENT OFFICE.

WARREN DAVID CALVERT, OF ALTOONA, PENNSYLVANIA.

TELEPHONE-ANSWERING INSTRUMENT.

1,368,481.

Specification of Letters Patent. Patented Feb. 15, 1921.

Application filed February 20, 1919. Serial No. 278,136.

To all whom it may concern:

Be it known that I, WARREN D. CALVERT, a citizen of the United States, and a resident of Altoona, in the county of Blair and State 5 of Pennsylvania, have invented certain new and useful Improvements in Telephone-Answering Instruments, of which the following is a specification.

My invention relates to improvements in 10 telephone answering instruments, and it consists in the constructions, combinations and arrangements herein described and claimed.

The foremost object of my invention is to provide an instrument to be used in conjunction with any telephone, to automatically answer the telephone upon the ringing of the local telephone bell.

A further object of the invention is to provide an instrument for the purpose described, 20 which has instrumentalities for raising the telephone receiver and speaking a stereotyped message into the transmitter both of said actions being automatically initiated upon the ringing of the telephone bell and 25 the energization of certain mechanism connected therewith.

A further object of the invention is to provide a device for the purpose described, including means whereby the telephone may 30 be "held" in order to give the occupant of the residence wherein the device is installed, time to get to the telephone to enter into conversation.

The fundamental object of the invention 35 is to provide a sound reproducing machine to be used in conjunction with any telephone, having means embodied therein for raising the telephone receiver and speaking a message into the transmitter, so that the 40 party at the other end of the line may know that the occupant is out and can be located at another telephone number; is engaged, or will return at some specified time, etc., these actions being automatically performed 45 by suitable means that is energized on the ringing of the telephone bell.

Other objects and advantages will appear 50 in the following specification, reference being had to the accompanying drawings, in

Fig. 1 is a perspective view showing the telephone answering instrument applied to an ordinary desk telephone,

Fig. 2 is a detail plan view of the receiver lifter,

Fig. 3 is a side elevation of the receiver lifter, and illustrating the two positions of the receiver support,

Fig. 4 is a cross section on the line 4—4 of Fig. 3,

Fig. 5 is a detail view illustrating the peculiar construction of the mouthpiece,

Fig. 6 is an end view of the mouthpiece, and

Fig. 7 is a detail diagrammatic view of 65 one form of relay switch that may be used in connection with the device.

Reduced to its fundamental principles, there are three basic elements that comprise the improved telephone answering instrument, namely, the relay switch 1, the motor driven phonograph 2, and the receiver lifter 70 3. So far as the relay switch is concerned, this does not directly form any part of the invention because any suitable relay switch 75 now on the market can be employed to serve the present purpose.

However, to make the operation of the relay switch clear, attention is directed to Fig. 7, wherein is diagrammatically shown 80 a relay switch which will be found suitable to start the motor of the phonograph and keep it running for a short time. Wires 4 are connected at one end to the ordinary telephone line wires 5 that lead to the call box 85 6 as shown in Fig. 1. An ordinary switch 7 embraced by the wires 4, is used to render the answering instrument inoperative when desired. This is accomplished simply by cutting the switch off.

A magnet 8 in the relay switch 1, attracts the armature 9 when the line wires 5 are energized to ring the telephone bell. The armature then moves up and engages the elongated contact 10 of the house current 95 wires 11.

Attached to the armature 9 is a plunger 13 which fits rather tightly in a cylinder 4 and is normally held down by a spring 15. The opening for the plunger at the top of the cylinders is large enough to enable the air to escape rapidly when the armature 9 is drawn upwardly. A minute hole in the bottom of the cylinder beneath the plunger 13 prevents the air from escaping rapidly 100 when the plunger is pressed down by virtue of the tension of the spring 15 after the ringing circuit ceases to energize the magnet 8.

It will be readily understood that the pur- 110

pose of the cylinder and plunger is to slowly draw the armature 9 from engagement with the contact 10 so as to cut off the current from the motor 16 of the phonograph 2, 5 after a short interval of time. The contact 10 is made long enough so that the circuit through the motor may continue long enough to enable a repetition of the message on the wax cylinder 17 of the phonograph into the 10 transmitter 18 of the telephone 19.

The phonograph 2 may be of any desired type and is preferably of as simple a design as can be obtained so as to keep the cost of the answering instrument low enough 15 for popular use. It will be observed that a flexible tube 20 leads from the sound box 21 of the phonograph to the mouthpiece 22. The mouthpiece is fitted over the transmitter as clearly shown in Fig. 5, and here it will 20 be observed that the mouthpiece 22 is of a peculiar shape.

The lower edge 23 is preferably cut away to leave an air channel 24. The opening thus provided not only makes it easier to 25 apply the mouthpiece to the transmitter 18 but also serves the important function of providing an air channel in communication with the outer atmosphere. It has been demonstrated that the result so far as clear- 30 ness of speech is concerned, it is better to leave such an air channel because if the mouthpiece 22 were entirely closed, there would be a muffling or damping effect on the diaphragm. The upper edge of the 35 mouthpiece 22 is curled over as at 24 so as to snugly fit the upper edge of the transmitter mouthpiece.

Practically the only modification of the phonograph 2 to accommodate the present 40 purpose is, to extend the shaft 25 of the mandrel to enable the attachment of the drive pinion 26. The pinion 26 drives the gear mechanism of the receiver lifter 3 which is illustrated principally in Figs. 1, 2 and 45 3, and to which attention is now directed.

An eccentric 27 on a countershaft 28 is arranged to tilt the receiver support 29 from the full line position to the dotted line position in Fig. 3 when the telephone bell rings, 50 and thereby to lift the receiver 30 and open communication to the transmitter 18 from the phonograph 2. The support 29 has a pan-like enlargement 31 on which the receiver rests. The eccentric 27 consists 55 simply of a circular disk with portions 32 cut away to bring the central contacting point 33 a sufficient distance in from the periphery of the disk to enable the support 29 to normally assume the full line position in 60 Fig. 3.

The countershaft 28 is driven by gears 34 which are of the required ratios to obtain a slow enough movement of the eccentric 27 in comparison to the speed of rotation of 65 the cylinder 17, and give time enough for

the speaking of a message once, twice, or more times, into the transmitter while the receiver 30 is raised. The receiver lifter includes the supporting frame 35 on which the various parts of the lifter are mounted. 70 The frame includes the pivot 36 in which the support 29 is journaled. The frame also includes the standard 37 to which the locking detent 38 is pivotally secured.

The detent 38 is normally held away from 75 the support 29 by a latch 39 of any suitable description. Under ordinary circumstances the detent 38 is positively held away from the support 29. However, should a circumstance arise wherein the occupant of the 80 house may desire to answer the telephone in person and still be unable to come to the telephone at the moment the bell rings, the latch 39 is unloosened, thus leaving the detent 38 free to swing over the end of the support 29 when the receiver lifter mechanism operates to lift the receiver 30. It can now be readily understood that when the receiver is lifted as indicated by the dotted line position of the support 29 in Fig. 3, the detent 90 85 95 will readily swing across the rear end of the support and prevent it from returning to the original position even after the eccentric 27 again reaches its original position.

The operation. 95

Immediately upon the ringing of the telephone bell in the call box 6, the magnet 8 in the relay switch 1 is energized and attracts the armature 9, whereupon current from the 100 wires 11 energizes the motor 16 and the phonograph 2 starts operation. It will require but few turns of the mandrel of the phonograph to carry the eccentric 27 past one or the other of the flat places 32, whereupon the periphery of the eccentric will bear on the rear end of the support 29 and lift the receiver 30. 105

The phonographic cylinder 17 is prepared with certain stereotype messages, for example: "Mr. Phillips is out and will return in ten minutes," or "Mr. Smith is busy; please call again in ten minutes," etc. These messages can be arranged on the phonographic cylinder 17 in any desired way, for instance, one cylinder may have various 115 kinds of messages to serve different purposes, arranged in zones, and preferably these messages will be recorded on the cylinder perhaps three or four times so as to make sure that at least one will be understood by the 120 party calling.

Contact is maintained in the relay switch 1, long enough to permit the various parts of the instrument to perform their proper function, and obviously, in a device of this kind there are always certain parts that will require further development and refinement in the actual building thereof. It is thought sufficient for the present purpose to set forth a generally operative device, the various ele- 125 130

ments of which being capable of use therein in the manner already described.

The advantages.

- 5 It is a matter of common experience to make a telephone call with the only reward at the end of a tedious wait, to hear the report that the other party will not answer. This comes not infrequently from the fact 10 that the other party is either out or is so otherwise engaged that he cannot get to the telephone while the bell is ringing. With this improved telephone answering instrument, the party calling is instantly rewarded 15 with an answer advising him that the party to whom he desires to speak is out, may be located at another telephone number, or otherwise engaged, and he need not lose valuable time in awaiting an unfavorable report from 20 the telephone operator.

It is thought needless to enlarge further upon the benefit and advantages of the answering instrument, it being thought sufficient to say that it is capable of almost 25 universal application and also of popular use because of its comparative simplicity and cheapness.

While the construction and arrangement 30 of the telephone answering instrument as herein described and illustrated is that of a generally preferred form, obviously, modifications and changes may be made without departing from the spirit of the invention or 35 the scope of the claims.

35 I claim:—

1. The combination, of a telephone transmitter, receiver and ringing circuit; and an automatically operating answering instrument, comprising a phonograph with motor 40 drive mechanism, and a cylinder having a recorded message, a reproducer in communication with the transmitter to conduct a spoken message thereto, and lifting mechanism on a part of which the receiver is 45 placed, operatively associated with a part of said drive mechanism, to lift the receiver in the initial operation of said drive mechanism, the motor of said mechanism being in electrical association with and under the 50 control of said ringing circuit.

2. The combination, of a telephone transmitter, receiver and ringing circuit; and an automatically operating answering instrument, comprising a phonograph with motor 55 drive mechanism, and a cylinder having a recorded message, a reproducer in communication with the transmitter to conduct a spoken message thereto, lifting mechanism on a part of which the receiver is placed, 60 operatively associated with a part of said drive mechanism, to lift the receiver in the initial operation of said drive mechanism, the motor of said mechanism being in electrical association with and under the control of said ringing circuit, and means re-

leasable when desired, into association with the receiver lifting part, to hold the receiver up independently of other parts of the lifting mechanism.

3. The combination, of a telephone transmitter and receiver, including the ringing circuit; and a sound reproducing machine with a motor-driven gear train in operative communication with the transmitter, lifting means on which the receiver is placed, 70 and means included in said train, for actuating the lifter on the initial operation of said machine and again lowering it at a predetermined time, said machine being initiated in its operation on the energization of 75 the ringing circuit, and means capable of being operatively disposed to the lifting means when desired, to hold the receiver up independently of said actuating means.

4. The combination, of a telephone transmitter and receiver, including the ringing circuit; and a sound reproducing machine with a motor-driven gear train in operative communication with the transmitter, lifting means on which the receiver is placed, 80 means included in said train, for actuating the lifter on the initial operation of said machine and again lowering it at a predetermined time, said machine being initiated in its operation on the energization of 85 the ringing circuit, and means capable of being operatively disposed to the lifting means when desired, to hold the receiver up independently of said actuating means, and an automatically operating relay switch in connection with the ringing circuit and said sound reproducing machine, for stopping said machine after a predetermined time.

5. An automatic telephone answering instrument, comprising a sound reproducing 105 machine with means arranged to be connected to the transmitter of a telephone to issue sounds into the transmitter, a telephone receiver lifting mechanism including a pivoted support with a receiver placed on one 110 end, and means bearing on the other end, arranged to be actuated by the sound reproducing machine to rock said support.

6. An automatic telephone answering instrument, comprising a sound reproducing 115 machine with means arranged to be connected to the transmitter of a telephone to issue sounds into the transmitter, a telephone receiver lifting mechanism including a pivoted support with a receiver placed on 120 one end, means bearing on the other end, arranged to be actuated by the sound reproducing machine to rock said support, and a member normally held back, but releasable when desired, to engage a part of said receiver lifting means and hold the receiver lifter stationary when the receiver is lifted.

7. In an automatic telephone answering instrument, the combination of a telephone

transmitter, and a sound conducting member including a mouth-piece arranged to fit over the transmitter, and having a portion cut away on the lower edge to leave an air channel.

8. An automatic telephone answering instrument, comprising a sound reproducing machine having a sound record, with a reproducer provided with a sound conducting connection arranged to be attached to a transmitter; a receiver lifter comprising a frame, a movable receiver support for sup-

porting a receiver, mounted on the frame; means engaging a portion of said support enabling it to assume a normally lowered 15 position, and arranged upon movement to move the support and raise the receiver, actuating means for said movable engaging means, operatively connected with a moving part of said reproducing machine, and 20 releasable latch-held means arranged to cooperate with said support to hold the receiver up at predetermined times.

WARREN DAVID CALVERT
